COMBINED FIREPLACE AND HEATER

Bernard R. Rose, Sherman Oaks, Calif., assignor to Dyna Manufacturing Co., Los Angeles, Calif., a corporation of California

Filed Jan. 14, 1963, Ser. No. 73,170

Term of patent 14 years

(Cl. D81—7)

FIGURE 1 is a front elevation of my combined fireplace and heater showing my new design;

FIGURE 2 is a side elevation of FIGURE 1;

FIGURE 3 is a top plan view of FIGURE 1;

FIGURE 4 is a bottom plan view of FIGURE 1.

The undisclosed side is substantially the same in appearance as the side shown and the rear is substantially plain.

I claim:

The ornamental design for a combined fireplace and heater, substantially as shown and described.
